Henry Williams

UNITED STATES PATENT OFFICE.

HENRY B. LEACH, OF BOSTON, MASSACHUSETTS.

SELF-CLOSING FAUCET.

SPECIFICATION forming part of Letters Patent No. 340,329, dated April 20, 1886.

Application filed January 21, 1886. Serial No. 189,241. (No model.)

To all whom it may concern:

Be it known that I, HENRY B. LEACH, of Boston, in the county of Suffolk and State of Massachusetts, have invented new and useful

5 Improvements in Self-Closing Faucets, of which the following is a specification.

In the accompanying drawings, in which similar letters of reference indicate like parts, Figure 1 is a vertical section of a faucet embodying my invention. Fig. 2 is an elevation of parts of the casing, diaphragm, valve-stem, and one of the rollers, the cap having been removed. Fig. 3 is a vertical section taken on a line at right angles to the line of the section in Fig. 1. Fig. 4 is a plan view with the cap removed. Fig. 5 is a plan view of the under side of the cap. Fig. 6 is a perspective view of one of the rollers. Fig. 7 is a view of the diaphragm provided with a slight modification. Fig. 8 is a vertical section showing further modifications. Fig. 9 is an edge view of one of the rollers. Fig. 10 is a sectional detail view showing a change in the shape of the rollers.

25 A is the body or casing of the faucet, provided with the nozzle A' and inlet-tube A".

B is the cap, held in position on the casing by the screw b and washer c, the latter encircling and the former screwing into the stem

30 C, which passes up through said cap. The valve-stem C is provided with the valve D, packed at D', the packing D", and the spring E.

F is the handle integral with the cap B.

H is a diaphragm bored centrally to allow 35 the passage of the stem C, screwed into the casing A, and provided with shoulders H', which rest on the upper edge of the casing within the cap.

I is an annular stop for limiting the motion 40 of the valve-stem. The upper surface of the diaphragm H is provided with the double inclines h—that is to say, the circular path or track surrounding the valve-stem has four inclines, preferably straight, as shown in Fig. 2,

45 but, if desired, concave, as shown in Fig. 7, the two apexes h' being opposite each other, and the two lowest points, h", being opposite each other. The under side of the cap, which is opposite and over the diaphragm, is provided with double inclines k, exactly similar to the double inclines h, so constructed and ar-

ranged that the apexes k' are exactly opposite the apexes h', and the points of greatest depression, k", are exactly opposite the lowest points, h".

55 L are rollers placed freely between the two sets of inclines and within the shell of the cap B. These rollers may be of any desired shape, provided of course that they are round. In Figs. 2, 3, 6, and 9 they are of convex disk 60 shape, in Fig. 10 they are flat disks, while in Fig. 8 they are spherical or balls. When the handle F is turned and partial rotation imparted to the cap, and hence to the inclines on the under side thereof, the rollers roll up the 65 inclines h on the diaphragm and the cap is lifted, thus raising the valve-stem and allowing the water to pass through the faucet. The pressure of the spring E draws down the valve-stem when the handle is released, and closes 70 the faucet in the ordinary manner, the rollers rolling back from the apexes of the inclines to the lowest points thereof.

It will be observed that the rollers L, whether of the shape shown in Fig. 6, 8, or 10, are 75 rollers in the strict sense of the term, and not wheels, as they travel on their peripheries, but do not rotate on their axes.

If desired, the path of the rollers may be 80 grooved out, as at P, Figs. 8 and 10.

The effect of the rollers placed between the reverse inclines is to reduce the friction when the valve-stem is moved to a minimum, so that the moving parts are always operative without the aid of a lubricant.

85 Having thus fully described my invention, what I claim, and desire to secure by Letters Patent, is—

1. In a self-closing faucet, the combination, with the reverse inclines or sets of inclines 90 placed opposite each other, one of which inclines or sets of inclines is capable of partial rotation, of one or more intermediate free rollers, substantially as and for the purpose set forth.

2. The combination of the rotary cap B, provided on its under side with a curvilinear track, the stationary diaphragm H, supported by the body of the faucet, and provided on its upper surface with a curvilinear track, said tracks 100 having their similarly-formed points of elevation and depression located opposite to each

other, the free rollers L, placed between the tracks, the valve-stem C, and the spring E, all arranged to operate substantially as shown and described.

- 5 3. The combination of the cap B, provided on its under side with one or more inclines, k, the diaphragm H, supported by the body of the faucet, and provided on its upper surface with one or more inclines, h, and one or more free rollers, L, placed between the inclines on the cap and the inclines on the diaphragm, substantially as and for the purpose set forth.
- 10 4. The combination of the cap B, provided

on its under side with the double inclines k, the diaphragm H, supported by the body of the faucet, and provided on its upper surface with the double reverse inclines h, and the free rollers L, placed between the double inclines on the cap and the double inclines on the diaphragm, substantially as and for the purpose set forth.

HENRY B. LEACH.
